REISSUED

UNITED STATES PATENT OFFICE.

MAX BROWN, OF CHICAGO, ILLINOIS, ASSIGNOR TO NATIONAL ART NOVELTY COMPANY, OF CHICAGO, ILLINOIS, A CORPORATION OF ILLINOIS.

DESIGN FOR A MIRROR.

51,916.

Specification for Design.

Patented Apr. 2, 1918.

Application filed December 11, 1917. Serial No. 206,715. Term of patent 7 years.

To all whom it may concern:

Be it known that I, MAX BROWN, a citizen of the United States, residing at Chicago, in the county of Cook and State of Illinois, have invented a new, original, and ornamental Design for a Mirror, of which the following is a specification, reference being had to the accompanying drawing, forming a part thereof.

The figure is a front elevational view of a mirror, showing my new design.

I claim:

The ornamental design for a mirror, as shown.

MAX BROWN.
